UNITED STATES PATENT OFFICE.

THOMAS M. WOOD, OF STAMFORD, CONNECTICUT.

NON-REFILLABLE BOTTLE.

SPECIFICATION forming part of Letters Patent No. 757,707, dated April 19, 1904.

Application filed August 10, 1903. Serial No. 168,954. (No model.)

To all whom it may concern:

Be it known that I, THOMAS M. WOOD, a citizen of the United States, residing at Stamford, county of Fairfield, State of Connecticut, have 5 invented a new and useful Non-Refillable Bottle, of which the following is a specification.

My invention has for its object to provide a simple, inexpensive, and thoroughly practicable stopping device which when applied to 10 an ordinary bottle will render said bottle practically non-refillable. With this end in view I have devised the simple and novel bottle-stopping device which I will now describe, referring to the accompanying drawings, forming 15 a part of this specification, and using reference characters to indicate the several parts.

Figure 1 is a section of my novel stopping device applied to a bottle and in the normal or closing position; and Fig. 2 is a similar 20 view, the bottle being in the pouring position.

My novel stopping device comprises four essential parts as follows, to wit: a ball-seat, which I have indicated by 10, a ball, (indicated by 11,) an inner (tube indicated by 12,) and an 25 outer tube (indicated by 13,) said tubes being in practice of suitable relative diameter to leave an ample pouring-space between them, which I have indicated by 30.

14 denotes a bottle having the usual neck 15 30 and flange 16.

So far as my novel stopping device is concerned the bottle may be of any ordinary or special design. The stopping devices may be made of standard sizes and will fit bottles of 35 standard sizes or may be made specially to fit any desired size and style of bottle. The inner and outer tubes are made of metal, and the ball-seat is likewise a tubular piece of metal having an opening 17 through it of less 40 diameter than the seat proper, and at its upper end a flange 18, which is adapted to rest upon the top of the neck of the bottle. The outer edge of the flange is shown as screw-threaded, as at 19, the body of the seat fitting 45 closely within the neck of the bottle, as shown. The ball may be made of any suitable material, and the seat is made concave to correspond with the convexity of the surface of the ball. The inner tube is provided with a closed 50 top, as at 20, an upper series of slots, (indicated

by 21,) a lower series of slots, (indicated by 22,) a cross-pin (indicated by 23) lying between the series of slots, and at its lower end with an angle-flange 24, which is threaded internally and externally, the internal thread engaging 55 thread 19 on the flange of the seat and the external thread engaging an internal thread on the outer tube, as at 25. The outer tube is provided at its upper end with a flange 26, which may or may not be threaded and which 60 is adapted to be engaged by the flange of an ordinary cork-lined closing-cap, which I have indicated by 27. This closing-cap may form the seal of the bottle in transportation and before opening. To open the bottle, the operator 65 removes the closing-cap in the ordinary manner.

In applying my novel stopping device to a bottle the bottle is filled, then the seat is inserted into the neck of a bottle, the ball being 70 in place therein, then the inner tube is screwed down to place, the internal thread of the angle-flange engaging the external thread on the flange of the seat, then the outer tube, either with or without a closing-cap, is screwed 75 down to place, the internal thread of the outer tube engaging the external thread upon the angle-flange of the inner tube, after which the operation is completed by closing the lower end of the outer tube under the ordinary flange 80 on the neck of the bottle, as at 28.

The operation is as follows: Having removed the closing-cap, to pour the bottle is tilted in the usual manner. As soon as it has been tilted sufficiently to place the outer end 85 of the outer tube slightly lower than the inner end thereof the ball will leave its seat and will roll along the inner tube until its progress is stopped by the cross-pin, as in Fig. 2. The liquid will pass out from the inner tube, 90 through lower slots 22, into pouring-space 30 and will pass out at the outer end thereof. When the bottle is in the pouring position, the liquid is prevented from passing into the inner tube by the ball, which will lie in the 95 socket (indicated by 29) lying between the lower slots 22 and the cross-pin, the said lower slots and the cross-pin being so located relatively to each other that the mid-height of the ball will just lie at the ends of the slots and 100

completely close the socket, as in Fig. 2. As soon as the bottle is returned to its normal position the ball will drop down upon the seat and form a perfect closure, as in Fig. 1.

5 Should an attempt be made to fill an empty bottle by holding it horizontally or immersing it in a tank of liquid, the liquid would pass into the inner tube at the slots 21, which I have called the "upper" slots, that being their 10 normal position, and would carry the ball down to its seat, thus effectually preventing the passage of liquid into the bottle. The closed outer end of the inner tube effectually prevents at all times any tampering with the 15 ball by means of a wire or tool of any kind.

Having thus described my invention, I claim—

1. A bottle-stopping device comprising an outer tube adapted for attachment to a bottle, 20 a slotted inner tube secured to the outer tube, a ball-seat adapted to engage the bottle-neck and be attached to the inner tube and a ball adapted to travel along the inner tube and to engage the seat to close the bottle.

25 2. A bottle-stopping device comprising an outer tube for attachment to a bottle, a slotted inner tube closed at its outer end, a ball-seat adapted to engage the bottle-neck and a ball adapted to move outward in the inner tube in 30 pouring and to engage the seat when the bottle is not tilted.

3. A bottle-stopping device comprising an outer tube adapted for attachment to a bottle, an inner tube having upper and lower series 35 of slots and a cross-pin between said series of slots, a ball-seat adapted to engage the bottle-neck and a ball adapted to move outward in the inner tube when the bottle is tilted until stopped by the pin and to engage the seat when 40 the bottle is in its normal position.

4. A bottle-stopping device comprising an outer tube adapted for attachment to a bottle, an inner tube having upper and lower series of slots, a cross-pin below the upper series of 45 slots and a ball-socket between the pin and the lower series of slots, a ball-seat adapted to engage the bottle-neck and a ball adapted to move into the socket and prevent passage of liquid into the inner tube in the tilted position and to engage the seat when the bottle 50 is in its normal position, substantially as shown, for the purpose specified.

5. A bottle-stopping device comprising an outer tube and an inner tube with a pouring- 55 space between them, said inner tube having slots to permit passage of liquid from the inner tube into the outer tube in pouring and other slots to permit passage of liquid from

the outer tube into the inner tube when refilling is attempted, a ball-seat and a ball adapted 60 to pass into the inner tube in pouring and to normally engage the seat to close the bottle and prevent the entrance of liquid.

6. A bottle-stopping device comprising an outer tube and an inner tube with a pouring-space between them, said inner tube being closed at its outer end for the purpose set forth, and having upper and lower series of 65 slots and a cross-pin, for the purpose set forth, a ball-seat and a ball adapted to pass into the inner tube in pouring and to normally engage 70 the seat.

7. A bottle-stopping device comprising an outer tube internally threaded at its lower end, an inner tube having an angle-flange internally and externally threaded and engaging the outer tube, a ball-seat having a flange externally threaded to engage the flange on the inner tube and a ball adapted to pass into the inner tube in pouring and to engage the 80 seat to close the bottle.

8. The combination with the flange of a bottle-neck, of an outer tube secured thereto by closing the lower end of the tube under the flange, a slotted inner tube closed at its outer 85 end and secured to the outer tube with a pouring-space between them, a ball-seat engaging the neck of the bottle and secured to the inner tube and a ball adapted to pass into the inner tube in pouring and to normally engage 90 the seat.

9. The combination with the flange of a bottle-neck, of an outer tube secured thereto by closing the lower end of the tube under the flange, an inner tube which is closed at its 95 outer end, is secured to the outer tube and is provided with upper and lower series of slots and a cross-pin below the slots of the upper series leaving a socket between said cross-pin and the slots of the lower series, a ball-seat 100 engaging the neck of the bottle and secured to the inner tube and a ball normally engaging the seat to close the bottle and adapted to pass into the socket to permit passage of liquid into the outer tube in pouring and to prevent its passage into the inner tube, the slots of the upper series permitting passage of liquid 105 from the outer tube into the inner tube above the ball to seat the latter when refilling is attempted.

In testimony whereof I affix my signature in presence of two witnesses.
